ATTORNEY

UNITED STATES PATENT OFFICE.

CHARLES KITSCHELT, OF NEW YORK, N. Y., ASSIGNOR TO NICHOLAS MULLER'S SONS & CO., OF SAME PLACE.

DESIGN FOR CLOCK AND INKSTAND.

SPECIFICATION forming part of Design No. 11,813, dated June 8, 1880.

Application filed May 8, 1880. Term of patent 3½ years.

To all whom it may concern:

Be it known that I, CHARLES KITSCHELT, of the city, county, and State of New York, have invented a new and original Design for 5 Clock and Inkstand, of which the following is a full, clear, and exact description.

The nature of my design is fully represented in the accompanying drawing, to which reference is made.

10 This invention refers to an improved design for a clock and inkstand; and it consists of an ornamental base having a forward-projecting center portion for the ink-reservoir and upright pillars, terminating in fanciful busts, 15 which sustains between them a clock or other article.

In the drawing, A represents the base of my improved clock and inkstand, and A' a central forward-extending portion of less height, 20 which serves as the base for the ink-receptacle B. Back of the ink-receptacle is arranged a rack, C, for pen-holders, &c. The main portion of the base A carries at each end and 25 symmetrically to the central inkstand, B, up-right pillars D, which terminate in fanciful

busts D', between which a clock, E, is supported, the whole forming a very ornamental and striking design.

Having thus described my invention, I claim as new and desire to secure by Letters Patent—

1. The design for a combined clock and inkstand, consisting of a supporting-base having a central forward-projecting front portion for the ink-reservoir and ornamental side pillars 35 supporting a clock between them, as shown and described.

2. The design for a clock and inkstand, composed of a base, A, a central forward-extending portion, A', a rack, C, side pillars, D, with 40 busts D', and a clock, E, supported between the pillars, as shown and described.

In testimony that I claim the foregoing as my invention I have signed it this 20th day of April, 1880.

CHARLES KITSCHELT.
